UNITED STATES PATENT OFFICE

ROBERT B. HURT, OF CLEVELAND, TENNESSEE, ASSIGNOR TO HARDWICK STOVE COMPANY, OF CLEVELAND, TENNESSEE, A FIRM COMPOSED OF CHRISTOPHER L. HARDWICK AND COOKSEY H. HARDWICK

DESIGN FOR A GAS RANGE

Application filed December 10, 1931. Serial No. 42,022. Term of patent 7 years.

To all whom it may concern:

Be it known that I, ROBERT B. HURT, a citizen of the United States of America, residing at Cleveland, in the county of Bradley and State of Tennessee, have invented a new, original, and ornamental Design for a Gas Range, of which the following is a specification, reference being had to the accompanying drawings, forming a part hereof.

In the accompanying drawings:

Figure 1 is a perspective view of a gas range showing my new design.

Fig. 2 is a similar view of the upper portion of the same showing the burner grid section in the open or uncovered position. The sides of the range are plain.

I claim:

The ornamental design for a gas range, as shown and described.

ROBERT B. HURT. [L.S.]
